UNITED STATES PATENT OFFICE

RICHARD E. HALL, OF OLEAN, NEW YORK, ASSIGNOR, BY MESNE ASSIGNMENTS, TO
ARVEY-WARE CORPORATION, A CORPORATION OF DELAWARE

DEVICE FOR SEALING CONTAINERS

Application filed January 25, 1928. Serial No. 249,312.

The present invention relates to a device for applying covers, and seals therefor, to containers, and refers more particularly to an apparatus especially designed for quickly and easily applying and securely locking and sealing covers upon containers.

The cover which the device of the present invention is adapted to apply and securely lock to the container has cooperatively associated with it a metal band of substantial width adapted to encircle the wall of the container adjacent the rim thereof. Said band is provided with flanges extending inwardly at an angle from its upper and lower edges,

10 the upper flange being adapted to contact the upper surface of the cover while the lower flange is adapted to engage the container wall. The cover and band, before application to the container, are brought together in engagement as a unitary structure and are applied as a unit.

Briefly, the device of the present invention comprises a series of shoes adapted to surround the metal band and compress the same firmly against the container wall to diminish its diameter and cause it to tightly grip the wall of the container and embed the lower inwardly extending flange of the band in said wall. The device is efficient in use, permitting the cover to be rapidly attached and sealed in place. By the device of this invention, there is applied a permanent seal, stronger and more theft-proof than former seals.

Other features, advantages and objects of the invention will be more particularly apparent from the following detailed description.

In the drawings,

40 Fig. 1 is a fragmentary side elevational view illustrating a container with the sealing device, shown in section, in inoperative or open position, preparatory to the step of applying a cover, and seal therefor, to the container;

45 Fig. 2 is a view in section of the sealing device in operative or closed position;

Fig. 3 is a top plan view of Fig. 2;

50 Fig. 4 is a fragmentary sectional view of the device in open position, preparatory to

applying the cover, and seal therefor, to the container;

Fig. 5 is a fragmentary sectional view of the device in inoperative position in the act of sealing the container; and

Fig. 6 is a fragmentary sectional view of the container showing the cover sealed to the container subsequent to the use of the device of the present invention.

Referring more in detail to the drawings, 60 1 designates a metal frame of approximately the same peripheral size and shape as the top edges of the container on which it is used. An upstanding pin 2 may be suitably attached to the frame 1 having slidably mounted thereon a collar 3 having grooves 4 adapted to engage the ends 5 of levers 6. The collar 3 may be moved upwardly and downwardly on the pin 2 by means of levers 7 which may be pivoted at 8 on fulcrums 9 and also be 70 pivotally attached at 11 to ears 12 of the collar 3. The fulcrums 9 may be pivotally attached to the frame 1 at 10. Thus as the levers 7 are moved downwardly, the collar 3 is moved upwardly, carrying with it the ends 5 of the 75 levers 6. The levers 6 in turn may be pivotally connected, as illustrated at 13, to extensions 14 of the frame 1, and may be integrally or otherwise fastened to separate shoes 15, preferably having curved inner faces 16 80 adapted to conform with the contour of the side wall of the container to be sealed. The inner faces 16 of the shoes 15 may be beveled as shown in the drawings to cause the shoes to conform at all points in cross section with 85 the sloping wall of the container. It is obvious, of course, that the inner faces of the shoes may be flat and longitudinally straight where the device is to be used for applying a cover, and seal therefor, to a container having straight sides.

A suitable container 17 of substantial depth may be provided, which may, for instance, comprise felted or moulded fibre, wood, metal or the like. A cover 18 may be provided which may be of wood or any other material shaped to conform to the upper rim of the container. For the purpose of securely locking this cover 18 in position on the container, a metal band 19 may be associated

with it which has a body portion of substantial width and which is adapted to surround the wall adjacent the rim of the container. From the upper and lower edge, respectively, of the body portion of band 19 may inwardly project an upper flange 20 and a lower flange 21. The upper flange 20 is adapted to contact the upper surface of the cover 18 while the peripheral edge of the flange 21 is adapted to contact the wall of the container, preferably in such a manner that it bites into this wall to a limited extent. The band 19 may be split at one or more points, as illustrated at 22, to aid in its application to the cover 18, suitable means 23' being provided to secure the ends together.

In the operation of the device, the cover and band are first brought together and united into a unitary structure. This unitary structure, comprising cover and band, is then applied to the container and the device of the present invention placed thereon, the frame 1 resting upon the cover 18 and the shoes 15 hanging loosely in a position adjacent the metal band, the relative positions of the elements referred to being illustrated in Figs. 1 and 4. As the levers 7 are moved downwardly under the force applied, for instance by manual pressure, the collar 3 is moved upwardly, carrying with it the ends 5 of levers 6, which causes the shoes 15 to move inwardly to bear against the band 19 until the device assumes the position illustrated in Figs. 2 and 5 and the band has been decreased in diameter sufficiently to cause the lower flange 21 to bite into the wall of the container. The upward movement of the collar 3 may be regulated by the movable thumb screw 23 which may be threaded to pin 2. Sufficient pressure is applied against the band 19 by the shoes 15 to cause the former to diminish in diameter and tightly grip the container wall, causing the flange 21 to be embedded therein to more securely lock the cover 18 to the container.

It is to be understood that the use of the device of the present invention is not to be limited to the specific types of containers and covers herein described; for instance, the cover may be made entirely of metal and the cover and band may comprise one piece.

I claim as my invention:

1. In a closing device, a frame including a vertical stem, a slidable collar upon said stem, a plurality of levers cooperatively associated with the collar and diverging radially therefrom, a shoe mounted on the outer end of each lever, the shoes forming substantially an annular ring about the stem as an axis, means for simultaneously moving the shoes, and an adjustable stop positioned upon said stem for limiting movement of the collar.

2. A closing device, including in combination, a frame, a plurality of levers pivotally

mounted on the frame, a shoe mounted on one end of each of said levers, each end of each shoe being substantially contiguous to the ends of adjacent shoes, means for manually actuating said shoes to move same simultaneously towards the vertical axis of the frame, and adjustable means mounted on the frame on the vertical axis thereof for limiting the radial movement of the shoes.

In testimony whereof I affix my signature.

RICHARD E. HALL.
